UNITED STATES PATENT OFFICE.

ARTHUR J. DONOVAN AND FRANK POKORNY, JR., OF NEW YORK, N. Y.

GOVERNOR.

1,290,123.

Specification of Letters Patent.

Patented Jan. 7, 1919.

Application filed April 12, 1918. Serial No. 228,286.

To all whom it may concern:

Be it known that we, ARTHUR J. DONOVAN and FRANK POKORNY, JR., citizens of the United States, and residents of the borough of Manhattan, in the city, county, and State of New York, have invented certain new and useful Improvements in Governors, of which the following is a specification.

This invention relates to automatic governing means for internal combustion motors, wherein the fuel passage intermediate the carbureter and intake manifold is provided with a throttling device in the form of a free piston, actuated by the motor suction; which, in contracting the fuel passage, tends to exhaust the chamber in which said piston operates; and our improvements are directed to means whereby, when the free piston has been drawn toward the end of its upward, throttling stroke, its chamber is automatically opened to communication with the atmosphere, to thereby break the vacuum in advance of said piston and thus allow said piston to return by gravity against only the motor tension as rearwardly applied to an extended, or open position.

Other features and advantages of our said invention will hereinafter appear.

30 In the drawing:

Figure 1 is a vertical sectional view of our improved governing device.

Fig. 2 is a section on the line 2—2 of Fig. 1.

35 Fig. 3 is a vertical sectional view of a modified form of our governing device.

Fig. 4 is a section on the line 4—4 of Fig. 3, and

40 Fig. 5 is a detail, enlarged, of the vacuum control valve.

In the example of our invention presented in this application we have shown it to comprise a gravity valve, cylindrical in form, and functioning as a free piston under 45 the suction influence of the motor piston, in aspirating the fuel charges, to automatically limit the capacity of the fuel passage.

Thus, let 1 indicate the intake manifold of a motor and 2 the carbureter, these elements being connected by an intermediate, cylindrical communicating device composed of an upper portion 3, having flange 4, and a lower portion 5, having flange 6. The portions 3 and 5 may be united as by the 55 screw threads 7 and 8, and they have flanges 9 and 10, whereby they may respectively

be connected with the manifold and carbureter.

The lower portion 5 is shown as provided, at its upper end, with an internal, annular recess 11, in which is fitted a hollow, cylindrical member 12, that is seated upon the shoulder 13 forming the base of recess 11; while the thickness of wall of said member 12 causes it to extend into and contract the 65 passage through said portion 5. Also, said member 12 has an upper radial flange 14, that lies between and in abutting relation with the opposed ends of portions 3 and 5, although the diameter of said member 70 12 is less than the outside diameter of said opposed ends.

The portion 3, where it is provided with the thread 7, which is internal, is bulged out 75 annularly, as at 15, whereby an annular clearance 16 is provided between the outer surface of flange 14 and the portions 3 and 5.

This clearance 16 is intended to serve as an air passage and it has communication with the outside atmosphere through an 80 orifice 17 in portion 3.

A free piston, consisting of a tubular member 18, fits slidably within member 12, said piston however being of greater length than member 12, and having a lower radial 85 flange 19, that fits slidably within lower portion 5, below shoulder 13, and is limited, in its downward movement as by an inwardly extending flange 20 at the base of said lower portion 5. Thus an annular 90 chamber 21 is provided between flange 19 and the under surface of member 12, and is bounded concentrically by the exterior wall of tubular member 18 and the interior wall of lower portion 5, said chamber 95 being contractible and expandable respectively by the upward and downward movements of the free piston.

It will be understood that the tubular member 18 forms a section of the passageway, in the governing device, for the fuel charges, which are communicated from the carbureter to the motor, but the particular function of the free piston is to serve as a valve or throttle to control or regulate the 100 volumetric capacity of the fuel charges aspirated to the intake manifold per motor piston stroke. Therefore a series of small orifices 22, increasing in size in an upward direction, are provided in the wall of tubular member 18, to form a means of communication between the fuel passageway 110

and chamber 21; so that, under the suction pull of the motor, in aspirating its supply of carbureted air, some of the suction pull is caused to partially exhaust chamber 21 of the air therein and as applied against the rearward portion of said piston, and thereby serves to draw the free piston upwardly.

Mounted in the upper portion 3, as by radial arms 23, carried by a threaded ring 10 24, that is screwed into the top of said upper portion, is a depending cone 25, axially over and in spaced relation with the upper perimeter of tubular member 18, the spacing aforesaid being at the maximum to permit 15 unrestricted passage of fuel mixture when the free piston is seated in its lowermost position, as upon flange 20.

The range of movement of the free piston in the upward direction brings its perimeter 20 into near relation with the cone 25, where the fuel passage is restricted to the lowest throttling limit.

It is thus our purpose to enable the motor to receive full charges of fuel mixture, while 25 providing means to automatically cause that supply to be diminished under certain conditions of motor operation.

For instance, the free piston being a gravity valve, will, at low motor speed remain 30 in a low position because then the extent of the suction force exerted upon the chamber 21 will be insufficient to lift said gravity valve; but, as this suction force increases with the augmentation of motor piston 35 speed, then it will take effect upon the chamber 21, lifting the gravity valve and thereby restricting the area of the fuel passage, whereby the diminished volume of admitted fuel mixture will tend to slacken the motor 40 speed. In normal operation of the motor the free piston or gravity valve will be found to hover at an intermediate point in its range of movement for the supply of a volume of fuel mixture suited to a predetermined rate of travel.

When the motor speeds to the point of drawing the gravity valve upwardly to near its throttling limit, also contracting the chamber 21 to its limit, it becomes necessary 50 to enable the gravity valve to open very quickly for the introduction of ample fuel charges. Therefore we provide means for breaking the vacuum in chamber 21 by putting it in communication with the atmosphere.

Therefore the member 12 may be hollow, and its base 26 has an orifice 27, in which is seated a needle valve 28, whose stem 29 depends through and a predetermined distance 60 below said orifice, so that it may be met and raised by the upper surface of flange 19 when the free piston has risen to near the point of its maximum throttling action. The valve 28 is in this manner raised from its 65 seat, and, by means of an orifice 30 in flange

14, opening into clearance 16, it will be apparent that communication is established between chamber 21 and the atmosphere, by way of orifice 17.

Upon the establishment of this communication between the chamber 21 and the atmosphere, the vacuum in said chamber is broken and the free piston will fall at once by its own gravity against the motor tension applied rearwardly of said piston thereby 75 opening up the throttle and enabling the motor to aspirate satisfying fuel charges.

As the free piston thus falls, it releases the needle valve 28, which again becomes seated, and thus closes the chamber 21 again 80 to atmospheric influence.

In the modification shown in Figs. 3 and 4, in which views the same reference characters designate those parts of the device which correspond therewith in Figs 1 and 2; we 85 have introduced additional features, for the purpose of rendering the free piston more sensitive to its automatic control by the motor suction forces, thereby enabling the throttle to maintain a fairly steady fuel flow, 90 to satisfy a predetermined rate of piston speed in normal regulated travel of the motor vehicle.

Thus, in said modification, the free piston is in two parts, viz.: the tubular member 30, 95 slideable in cylindrical member 12^a, and co-acting, as a throttle with the cone 25; said member 30 having the orifices 22 which communicate with chamber 21; and the annulus 31, fitting slidably within the lower cylindrical portion 5, said annulus having an inward flange 32, which provides a seat for the radial flange 33 of member 30.

Where our improved governing device is employed with the open mouth type of carburetor, having an unrestricted fuel flow, we may provide, at the lower portion of the fuel passage, a centered choke device, as 34, serving to contract said passage, especially when the free piston is seated, by gravity, upon the base flange 20, at which time a concentric passage of minimum area is left between the choke device 34 and the adjacent portion of said free piston, for idling, with the throttle closed down.

The cylindrical member 12^a, seated within lower portion 5, is here shown as of skirt or inverted cup shape, to thus comprise an upward extension of the chamber 21; and the stem 29 of valve 28 depends into said chamber extension. It will be noted, in Fig. 5, that a knife edge seat 35 is provided for valve 28, and that the under surface of the valve seat material is cupped out at 36, with communicating orifices 37, this arrangement 125 being intended to facilitate the functioning of said valve.

While with the form of our device shown in Figs. 1 and 2 the free piston, when raised to the point of maximum throttle closure, 130

then opens valve 28, thus breaking the vacuum, so that said free piston will fall quickly by gravity to the full open throttle position; in the modified form of Figs. 3 and 4, the 5 operation is as follows:—

Upon starting up the motor, and with the exercise of suction in chamber 21, the two parts 30, 31 of the free piston will move upwardly together, the aspirating tension 10 of the motor overcoming the combined weights of these members, and the passage past the choke device 34 opening up, so that an adequate supply of fuel mixture is available. With the upward movement of the 15 free piston, throttling action occurs between it and the cone 25, and the tendency of the motor to race or run at an undesired speed is thus prevented. But the desideratum is to maintain as well as possible the hovering 20 position of said free piston at about the point where it will permit the passage of a duly regulated fuel flow.

Therefore the member 30 is relieved from the weight of the annulus 31 at a given 25 point in its path of travel, the annulus being checked at such point, where it is removed from the sustaining influence of aspirating force, while the member 30 is left free to continue its movement. As shown, the lower 30 edge 38 of member 12^a extends into the upward path of the annulus 31, so that when said annulus, in rising, meets the obstruction thus presented, it is arrested, and is then free to fall by gravity.

With the annulus arrested at its uppermost position, and then free to fall against only the motor tension as rearwardly applied, it will serve as a balance valve, to admit such fuel quotas as will satisfy the 40 motor at the governed speed. The member 30 will then also be free to drop as the motor slows down under governed speed.

Variations may be resorted to within the spirit and scope of our said invention and 45 parts thereof used without others.

We claim:—

1. Speed regulating means for internal combustion motors, comprising a gravity return, fuel control valve, adapted to operate 50 under the aspiratory pull of the motor and the exhausting of air from the forward path of said valve, whereby said valve is adapted to function in governing the volumetric fuel supply, and automatic means 55 for permitting the readmission of air in said forward path, thus enabling the gravity return of said valve.

2. In an internal combustion motor having a carbureter and a fuel passage, the combination of a gravity return, fuel control 60 valve, said valve adapted to be controlled through the character of the vacuum created

by variable motor speed, to govern the volumetric fuel supply, and automatic means, functioning when said valve is near the limit 65 of its throttling movement, to break the vacuum relatively to said valve, thus permitting its gravity return.

3. In an internal combustion motor having a carbureter and a fuel passage, a gravity return free piston comprising a throttle, said piston adapted to be actuated by the aspiratory pull of the motor, whereby the volumetric fuel supply is governed; and automatic means, operable when said piston is 75 near the limit of its throttling movement, to modify the influence of the aspiratory pull with relation to said piston.

4. In an internal combustion motor having a carbureter and a fuel passage, the combination of a gravity return, hollow, free piston, included in said passage, said piston adapted to function as a fuel throttle, a chamber in which said piston works, an air inlet to said chamber, a gravity valve normally closing said inlet, and means of communication between said chamber and passage, whereby the fuel raising suction pull of the motor also serves to operate said piston, and said piston, when near the end of 90 its throttling stroke, serves to open said valve, thereby diminishing the suction pull relatively to said piston, thus permitting said piston to return to a throttle open position.

5. In an internal combustion motor having a carbureter and a fuel passage, a two part free piston comprising a throttle, said piston adapted to be actuated by the aspiratory pull of the motor to operate said piston, whereby the volumetric fuel supply is governed, means for arresting the upward movement of one part of said piston independently of the continued movement of the other part thereof, and automatic means for relieving both piston parts from the influence 105 of the motor aspirating pull.

6. In an internal combustion motor having a carbureter and a fuel passage, a gravity return valve comprising a throttle, said valve adapted to function under the influence of the aspiratory tension of the motor, and automatic means operable when the valve is near the limit of its throttling movement, to partially relieve said valve from the influence of the motor tension.

Signed at the borough of Manhattan, in the city, county, and State of New York, this 9th day of April, A. D. 1918.
